UNITED STATES PATENT OFFICE.

FERRY M. FORBES, OF MILFORD, MICHIGAN, ASSIGNOR OF ONE-HALF TO
THOMAS W. COMMON, OF MOUNT CLEMENS, MICHIGAN.

BED ATTACHMENT FOR INVALIDS.

SPECIFICATION forming part of Letters Patent No. 618,407, dated January 31, 1899.

Application filed December 15, 1897. Serial No. 661,957. (No model.)

To all whom it may concern:

Be it known that I, FERRY M. FORBES, a citizen of the United States, residing at Milford, in the county of Oakland, State of Michigan, have invented certain new and useful Improvements in Bed Attachments for Invalids; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to a bed attachment for invalids; and it consists in the construction and arrangement of parts hereinafter fully set forth, and pointed out particularly in the claims.

20 The object of the invention is to provide simple and efficient means which may be attached to a bed of any construction and by means of which the invalid may be raised to a sitting posture or any desired inclination 25 and supported in said position without any jar or strain whatever, and a further means whereby a table may be provided in front of the invalid and raised to any desired height and which will also serve for a support when 30 at stool, if desired. This object is attained by the mechanism illustrated in the accompanying drawings, in which—

Figure 1 is a perspective view of a bed provided with my improved devices. Fig. 2 is a 35 central longitudinal section through the bed, showing manner of attaching the operative mechanism thereto. Fig. 3 is a side elevation, partly in section, a portion of the rail being broken away to more clearly show construction of parts and showing by dotted lines the adjustment of the table or support. Fig. 4 is an enlarged section through the bed-rail, as taken on line 44 of Fig. 3. Fig. 5 is a section on line 55 of Fig. 4. Fig. 6 is a perspective showing the detachable back-rest which is employed when the support is serving as a stool. Fig. 7 is an enlarged elevation of the cross-shaft employed to operate the mechanism alike on both sides of the bed and 45 which is longitudinally adjustable. Fig. 8 is

a transverse section through said shaft on line 88 of Fig. 7.

Referring to the letters of reference, A designates a supporting-frame, which may be formed of any suitable material, which is located at the head end of the bed and provided with suitable cross-strands *a*. This frame may be caused to lie upon the top of the mattress, as shown in Figs. 1 and 2, or it may be placed under the head of the mattress, as 55 shown in Fig. 3. The lower opposite corners of said frame are pivoted on opposite sides to the upper ends of the vertical standards *b*. These standards are vertically movable in suitable supports secured to the inner face of 60 the side rails *B* of the bed, so as to permit the supporting-frame *A* to be raised or lowered to enable it to be placed upon the mattress or beneath the mattress, as desired.

C designates a pair of angle-levers pivoted 70 at *c* to the inner faces of the side rails *B* of the bed. The upper ends of said levers have a movable connection with the side rails *d* of the frame *A* by means of suitable clips *e*, which embrace said rails and which carry 75 antifriction-rollers, (shown by dotted line *f* in Fig. 2 and by solid lines in Fig. 3,) which bear against the under edge of said rails and obviate undue friction between said movable parts. The lower ends of said levers *C* are 80 connected by means of links *D* with the depending ends of the arms *E*, which are fixed to opposite ends of the rock-shaft *F*. This shaft *F* is journaled at its opposite ends in suitable hangers or bracket-plates *G*, which 85 are secured to the opposite inner faces of the side rails *B* of the bed. One end of the shaft *F* passes through the plates *G*, in which it is journaled, and is provided with a right-angled end portion *h*, which projects outside 90 of the bed-rail and is adapted to enter the socket of the actuating-lever *H*, as shown in Fig. 4, by which means an actuation of the lever *H* will rock the shaft *F* and raise or lower the supporting-frame *A*, so that it may 95 be caused to lie in a horizontal position, as shown by dotted lines in Fig. 2, or caused to stand at any degree of inclination, as will be well understood.

To provide for locking the levers *C* so as 100

to maintain the supporting-frame A at any degree of inclination, I employ a suitable ratchet mechanism, (shown in Figs. 4 and 5,) which consists of a spring-actuated plunger 5 or detent *i*, which is mounted in a bracket I, attached to and adapted to move with the arm E. The upper end of said detent engages a ratchet J, fixed to the inner face of the outer plate of the hanger G.

10 Embracing the end *h* of the shaft F is a looped or bifurcated trigger *m*, which extends downward and is provided with a right-angled portion that passes through a vertical slot *o* in the bracket I and engages the upper end 15 of the coiled spring *o'*, which environs the pin or detent *i* and is attached at its upper end thereto. This trigger is actuated by means of a hand-grip *n*, pivoted on the upper end of the lever H and connected by a wire R with 20 a short pivoted arm *s* on the lower end of said lever, the free end of which engages the trigger *m*. Therefore by grasping the hand-grip the arm *s* is caused to depress the trigger *m*, which depresses the spring *o'* and carries the 25 detent free from the rack J, whereby the shaft is free to be rotated by means of the lever H to move the supporting-frame A to any desired position. Upon the release of the lever H the action of the spring *o'* will cause the 30 detent to reengage the rack J and lock said parts.

To provide for supporting the table or rest in front of the invalid when in a sitting posture, I employ on opposite sides of the bed 35 a pair of lazy-tongs or pivoted arms K. The lower end of one of said arms is pivoted at *v* to the side rail of the bed, while the lower end of the other arm is adapted to travel horizontally in a way formed by securing a 40 strip *t* to the inner face of the rail of the bed, said last-mentioned arm having an angle end *t'* projecting through said way, which is connected by means of a link *t''* with an arm *u*, fixed on a rock-shaft L, which crosses between the side rails of the bed and is journaled in suitable brackets L', secured thereto. One end of said shaft projects beyond the rail of the bed and is provided with a crank or angle portion *v'*, adapted to receive an 45 operating-lever *v''*, whereby by the actuation of said shaft L said arms K may be extended or folded together, so as to cause their upper ends to project at any desired elevation over the bed, as shown in Figs. 1 and 2, or to lie 50 folded against the side of the bed-rails, as shown in Fig. 3. The upper ends of the arms K are connected by cross-pieces K', to one end of which one of the arms is pivoted, the upper end of said arm being adjustably 55 secured thereto by means of a pin *b'*, adapted to slide in a slot *b''* in said cross-pieces, whereby the upper ends of said arms K are 60 permitted to move toward or from each other as they are raised and lowered through the 65 operation of the lever *v''*.

To provide for locking the arms K at any desired elevation, I employ a ratchet con-

struction similar to that shown in Fig. 4 and which serves to lock the shaft F. Therefore a minute description of this ratchet construction is unnecessary. Suffice to say that a similar trigger *m'* is employed to disengage the detent from the ratchet, which is actuated by the pivoted arm *s*, carried by the lever H, when said lever is placed upon the right-angled end *v'* of said shaft L. This arrangement permits the table P to be supported at any desired elevation.

The arm K, to which the connecting-link *t''* is attached and which moves back and forth in a way behind the strip *t*, is provided with an antifriction-roller *u'*, which travels upon the edge of said strip *t* and obviates undue friction.

A table P is placed upon the cross-pieces 85 K' of the supporting-arms K when raised and is employed for supporting dishes when serving meals to the patient and for other purposes. This table may also serve as a stool, as shown in Fig. 6, the table being slipped 90 under the patient when the arms are down, when said arms are raised a sufficient height to place a chamber thereunder. To support the patient at stool, a detachable back S is employed, as shown in Fig. 5, which is adapted 95 to engage the table P and may be readily removed when not in service.

The supporting-frame A, as will be seen in Fig. 3, may be placed under the mattress, so that the mattress and the bedding on which 100 the patient lies may be raised thereby.

As will be seen on referring to Figs. 7 and 8, the shaft F is composed of two parts, which are secured together by suitable clips *w*, which embrace the two parts of the shaft and hold 105 them together. By means of this construction the length of said shaft may be increased or decreased at will to accommodate the various widths of beds upon which the device is mounted. The shaft L, while not shown, 110 is similarly constructed.

By means of this improved device, which may be attached to any bedstead in use, every convenience of the patient may be served and the patient supported in a sitting posture or a 115 half-recumbent position without jar or strain, making the device especially adaptable for hospital use.

Having thus fully set forth my invention, what I claim as new, and desire to secure by 120 Letters Patent, is—

1. In a bed attachment for invalids, the combination with the bed-frame, the standards mounted in the sides of the frame to move vertically, the supporting-frame pivoted to 125 said vertically-movable standards, sliding clips mounted on the rails of said supporting-frame, the side levers pivoted to the frame of the bed and to said clip on said supporting-frame, and means for actuating said levers to 130 raise and lower said frame, substantially as set forth.

2. In a bed attachment for invalids, the combination with the bed-frame, the opposed

standards mounted to move vertically in said bed-frame, the supporting-frame pivoted to said vertically-movable standards, the levers pivoted to the bed independent of the pivot of the supporting-frame and engaging the upper end of said supporting-frame, the rock-shaft supported on the bed-frame, the links connecting said shaft with said levers, means for actuating said levers, and the ratchet for locking said levers in any desired position.

3. In a bed attachment for invalids, the combination with the bed-frame, the lazy-tongs or pivoted arms mounted on the bed-frame adjacent to said supporting-frame, one of said arms having a depending end which is adapted to travel in a way in the frame of the bed, a rock-shaft mounted on the frame of the bed, the link connecting said shaft with

said arms whereby said arms are actuated, and a support or table carried by said arms. 20

4. In a bed attachment for invalids, the combination with the bed-frame, of the pivoted supporting-frame mounted thereon, the pivoted levers having a sliding engagement with the upper end of said frame, the rock-shaft, the links connecting said shaft with said levers, said shaft being formed of two united parts to permit of longitudinal adjustment thereof, substantially as set forth. 25

In testimony whereof I affix my signature 30 in presence of two witnesses.

FERRY M. FORBES.
